UNITED STATES PATENT OFFICE.

WALTER S. MOODY, OF SCHENECTADY, NEW YORK, ASSIGNOR TO GENERAL ELECTRIC COMPANY, A CORPORATION OF NEW YORK.

THREE-PHASE TRANSFORMER.

1,141,199.

Specification of Letters Patent. Patented June 1, 1915.

Application filed April 8, 1903. Serial No. 309,631.

To all whom it may concern:

Be it known that I, WALTER S. MOODY, a citizen of the United States, residing at Schenectady, county of Schenectady, State 5 of New York, have invented certain new and useful Improvements in Three-Phase Transformers, of which the following is a specification.

Heretofore there have been in general use 10 three methods of cooling stationary electrical transformers. In one method in practically universal use, with transformers of small capacity, the core and windings of the transformer are immersed in a bath of a suitable insulating fluid such as oil contained in a receptacle, the bath of oil being raised upon to convey heat from the core and windings of the transformer to the walls of the receptacle from which the heat is dissipated by radiation. In a second method the core and windings of the transformer are immersed in a bath of oil as in the first method described, but additional cooling means for the oil is provided in the nature 15 of a coil of pipe also immersed in the oil through which a cooling fluid such as water is circulated. In a third method the core and windings of the transformer are cooled by a blast of air forced against them by a fan blower or other air-circulating device. I have found, however, that in some cases and particularly with transformers of very large capacity, excellent results may be obtained 20 by placing the core and windings of the transformer in a case or receptacle and causing a forced circulation of oil or other insulating fluid to take place through said receptacle, cool oil being continuously admitted into the receptacle and hot oil drawn off. The heated oil may advantageously be 25 cooled without the receptacle by passing it through suitable cooling apparatus, after which it may be again passed through the receptacle containing the transformer. This 30 method of cooling, broadly speaking, has been suggested before but has never gone into extensive use. Certain practical difficulties heretofore experienced with this method of cooling are avoided by the use of my present invention.

The last-mentioned method of cooling possesses certain important advantages. With oil as the cooling fluid, the insulation of the

transformer is improved. With this method the size of the containing receptacle may be 55 made much smaller than in a transformer of the same capacity in which the oil is cooled by a coil of water pipe located in the receptacle, a feature of considerable importance with transformers of very large capacity. 60 Usually the amount of oil necessary is less with the method of cooling described hereinafter than where a coil of water pipe immersed in the bath containing the transformer is employed. 65

By the use of a circulating body of oil as the cooling agent for the transformer, the temperature of different parts of the transformer may be kept more uniform than is possible when no means are employed for 70 obtaining a forced circulation of the oil. In order to obtain the best results in this direction, I have provided means for insuring that the circulation of oil taking place in the neighborhood of the various parts of the 75 transformers shall be proportioned to the necessities of the case. For instance, I have arranged so that a more rapid circulation takes place by the windings of the transformer than by the core, since the insulation 80 for the windings is a poor conductor of heat and also because it is usually desirable to maintain the temperature of the windings and insulation lower than is necessary for the core. I have also arranged so that all 85 parts of the transformer winding and core, except in some cases the leads, are submerged at all times. In some cases I entirely fill the containing receptacle with oil. In order to avoid the presence of air bubbles in the oil 90 in the normal operation of the transformer, I have arranged so that in all cases the oil drawn out of the transformer containing receptacle, while taken from the portion of the receptacle containing the hottest oil, shall 95 be taken from a point below the level of the oil so that no air may be sucked into the outlet passage of the transformer receptacle.

When, as in the embodiments disclosed in my present application, my invention is applied to a multiphase transformer, I provide means for obtaining a separate flow of oil through the windings of each phase of the transformer and through the adjacent core portions, thus assuring a proper cooling of 100 each part of the transformer. The embodi-

ments of my invention disclosed herein contain many novel features of construction and arrangement, some, but not all of which, are peculiar to the method of cooling employed in the present instance by me.

The various features of novelty which characterize my invention are pointed out with particularity in the claims annexed to and forming a part of this specification. For a better understanding of my invention, however, and the advantages possessed by it, reference may be had to the accompanying drawings and descriptive matter in which I have described in detail forms in which it may be embodied.

Of the drawings, Figure 1 is a side elevation partly broken away and in section showing a three-phase transformer of large size; Fig. 2 is a sectional elevation at right angles to Fig. 1; Fig. 3 is a sectional elevation on the line 3-3 of Fig. 1; Fig. 4 is an end elevation partly in section showing the core and winding of the transformer; Fig. 5 is an elevation of a portion of the core and winding of a transformer differing from that shown in Fig. 4 in the arrangement of the means for forming the ventilating passages for the windings; Fig. 6 is a partial elevation of a spacing member used in the construction shown in Fig. 5; Fig. 7 is an end elevation partly broken away and in section of a transformer in which the laminæ are vertically disposed; Fig. 8 is a plan showing the manner in which the punchings of the three-phase transformer core may be assembled; Fig. 9 is a diagrammatic representation of the oil circulating and cooling system; and Fig. 10 is a perspective view partially broken away, showing on a larger scale and more in detail a portion of the coils and the insulation surrounding the same.

Referring to the drawings, 1 represents the case, tank or receptacle of a three-phase shell-type transformer of large capacity. The receptacle comprises a base portion 2 which may advantageously be formed out of cast iron, a body portion 3 which may advantageously be formed of sheet metal, and a cover portion 4 preferably formed of cast iron. Suitable means such as bolts 5 are employed for detachably securing the cover 4 to the body 3 in such manner as to form an oil-tight joint between the cover and the body. The body 3 and the base 2 are connected together in any suitable manner as by rivets 6 to form an oil-tight joint between them. The cover is provided with suitable man or hand-hole openings, the covers 7 for which may be secured to the cover by bolts 8 so that oil-tight joints between the covers 7 and the main cover 4 are obtained.

The transformer core is made up of laminæ assembled in a frame preferably formed of structural iron. In the construc-

tion shown the frame is formed of top and bottom beams 11 riveted to top and bottom side beams 12 and 12' respectively. As shown, suitable wooden space blocks 13 may be placed between the core and the beams 11, 12 and 12'. In the construction shown the beams 11 and 12' are of the form known as I-beams. The top side beams 12 are formed each of two channel bars between which are connected members 14. The beams 12 and 12' are connected by tie bolts 15. The transformer core is normally suspended from the cover member 4 by means of links or members 16 secured at their lower ends to the members 14. The upper ends of the links 16 are threaded and pass through apertures formed for the purpose in the transformer cover to engage nuts 17 which bear against bosses formed for the purpose on the upper surface of the transformer cover. Supports 18 carried by the base member 2 are provided, upon which the beams 12' may rest when desirable as when the transformer is being transported. Under these circumstances it will be understood that the nuts 17 are eased up sufficiently to allow the beams 12' to engage the supports 18. It will be understood that suitable provision may be made for obtaining oil-tight joints where the bolts 17 pass through the cover 4.

The core is formed with three pairs of vertically-extending slots or passages 19 for the windings. The primary coils 20, and secondary coils 21 forming the winding for a phase, pass through the corresponding pair of slots or passages 19 and surround the intermediate core portion 22. As shown, the winding for each phase is surrounded by a box-like structure or casing 23 open at the top and bottom and provided with portions 24 surrounding the core portion 22. This may be better seen by referring to Fig. 10, where it will be seen that the portions 24 consist of flat members running parallel to the sides of the portions of the core enclosed by the coils, portions 24 extending until they come in close proximity with the outside casing 23. In order to hold the casing 23 and the portions 24 in position, there is wound around them a suitable webbing or other material 124, spacers 25 being placed outside of this webbing and between it and the core. The webbing which is illustrated in this drawing is merely for the purpose of binding the casing 23, portions 24 and the coils into a compact unit and forms no portion of my invention. The box 23 is separated from the adjacent laminæ edges by spacers 25 so as to form core ventilating spaces or passages between the box and the core independent of the ventilating spaces for the coils. Surrounding the lower ends of the boxes or receptacles 23 are box-like members 26 which may advantageously be

formed of sheet metal and are secured to the framework in which the transformer core is held. Tight joints are made between the upper edges of the boxes and the under 5 surface of the core. Above the transformer core proper and the upper ends of the casings 23 are supported bars 27 which may advantageously be formed out of wood. The bars 27 form means for supporting suitable 10 bushings 28 for the leads from the separate coils of the transformer. Terminal leads 29 which may be connected to the coil terminals in any suitable manner as the service conditions may require, pass out through the cover of the transformer through bushings 30. It will be understood that the joint 15 between each bushing 30 and the cover, and between the bushing and lead passing through it, may be made oil-tight.

20 The primary and secondary coils for each phase of the transformer may be subdivided and interspersed in order to obtain the most efficient disposition of conducting material. Spacers are placed between adjacent sections 25 of the windings and between the outer portions of the windings and the inclosing box 23 to form ventilating passages extending transversely to the laminæ. These spacers may be in the form of long 30 strips 31 extending transversely to the laminæ as shown in Fig. 4 and in Fig. 10. Instead of spacers of this type, I may use spacers as shown in Fig. 5 in which each 35 spacing member is in the form of an arm 31' extending parallel to the laminæ and engaging the appropriate portions of the windings. The arms 31' at one edge of one portion of the windings may be integrally connected together and may be formed from 40 a blank consisting of a strip 31'' of box-board or the like of the shape shown in Fig. 6.

Each strip 31'' bears against an inner or outer edge of the proper winding section or 45 portion, and the opposing pairs of arms 31' from each strip 31'' bear against opposite sides of the winding section. As shown, the arms 31' do not extend entirely across the sides of the windings which they engage, 50 and the arms 31' from strips 31'' at opposite edges of the same winding section overlap one another. This not only gives a better cooling flow of the oil, but improves the mechanical construction, since the turns 55 of the windings are prevented from lateral displacement by the arms 31'. This is a feature of considerable practical importance in some cases, since the conductors are sometimes subject to considerable force tending 60 to displace them, as when the system in which the transformer is connected becomes short-circuited. Under such conditions the insulation which normally holds the turns of the coils in place cannot always 65 be relied upon.

A supply pipe 32 passing through the cover member 4 connects at its lower end with a pipe 33 from which connections 34 lead one to each box 26. The oil entering the transformer through the pipe 32 passes 70 into the boxes 26 and from there a portion of the oil passes up through the windings located within the casing 23, and another portion passes upward into the spaces between the outer surface of the casing 23 75 and the inner walls of the conductor-receiving slots of the core—that is, the casing 23 acts as a division wall to direct the flow of oil. In order to obtain a more thorough cooling of the core I may build up the 80 transformer core of horizontal bundles of laminæ separated by suitable spacers 10 so as to form ventilating passages or spaces 10' communicating with the passages between the box 23 and the inner edges of the 85 laminæ as best shown in Fig. 4. When this construction is employed I prefer to arrange the spacers 10 so that the passages 10' between adjacent bundles of laminæ 9 increase in thickness from the bottom of the 90 core upward, as illustrated in Figs. 4, 5 and 7 since otherwise the greater pressure of the incoming oil at the bottom of the transformer would cause an undue proportion of the oil to pass through the lower core 95 spaces.

The oil circulation system may be arranged so that the oil entirely fills the receptacle 1. In some cases, however, I merely fill the receptacle to the level shown in Fig. 100 3. The heated oil is carried out of the transformer case in any suitable manner as through a pipe 35, the upper end of which terminates an appreciable distance below the oil level in the receptacle. In the construction shown, the lower end of the pipe 35 communicates with a chamber 36 formed in the case base 2. For convenience a passage 37 may be formed in the base 2 below the floor level which leads from the chamber 110 36 to the exit orifice 38.

In order to insure that the oil level shall always be above the upper end of the pipe 35, I provide a valve 39 which is normally held closed except when the oil level is such 115 that a float 40 connected to the valve lever 41, one end of which is pivotally connected to a fixed member 41', is raised, thus opening the valve 39.

Referring to Fig. 3, it will be seen that 120 valve 39 consists of an upper member 39², making an oil-tight joint 39' with the top of pipe 35. Fastened to this member is a lower portion having ribs 39³ between which are openings, not shown, permitting 125 oil to flow through them and into the pipe. Float 40 has a U-shaped member 40' in operative relation with lever 41 arranged so that as the float rises with the rise of the oil level, the free end of the lever will be raised, 130

thus raising the valve and opening the joint 39', allowing oil to flow between ribs 39² into the pipes. As the oil level is lowered, float 40 will descend carrying with it the 5 free end of lever 41, and, after the lever has reached a certain point, joint 39' will be closed, thus preventing the further outflow of oil. The oil level in the arrangement shown in Fig. 3 is just at the stage at which 10 the valve 39 will be opened upon any increase in the amount of oil in the case 1. With this arrangement there is no tendency for air to be undesirably sucked into the pipe 35, and thereby dissolved in the oil. 15 To provide for removing oil from the transformer whenever desired, I have provided a drain pipe 42 leading from the bottom of the case. This pipe is normally closed by a valve 43. Drain pipes 44 extending from 20 the boxes 26 are provided, each with a valve 45, normally held closed. Each valve 45 can be opened by means of a suitable operating means 45' leading through the cover of the transformer whenever it is desired to 25 allow the oil to drain out of the boxes 26.

In the diagram view shown in Fig. 9, I have illustrated a cooling system arranged for supplying cold oil to, and removing hot oil from, a battery of two transformers each 30 of which may be similar to the transformer hereinbefore described and illustrated. As shown the oil supply pipe 32 of each transformer, each of which is provided with a check valve 32' and manually-operated con- 35 trol valve 32'', receives oil from a pipe 46. The pipe 46 is connected by a pipe 47 to the discharge pipes 48 of two similar cooling devices 49. Each pipe 48 may be independently closed by a manually-operated valve 48'. Pipes 51 leading from the discharge orifices 38 of the transformers, each of which may be closed by a manually-actuated valve 52, are connected to a pipe 53 which in turn is connected to a pipe 54. The pipe 45 54 may be connected or disconnected at will by valves 55 and 56, to the inlet pipes 57 and 58 respectively, of two oil pumps 59 and 60. A manually-actuated valve 61 is employed by which the inlet pipe 58 of the 50 pump 60 may be opened or closed at will. The discharge pipe 62 from the pump 59 is connected to inlet pipes 63 of the cooling device. Manually-actuated valves 64 form means for opening or closing the connection 55 between the pipe 62 and either inlet pipe 63 at will. An oil reservoir 65, located at a level above that of the remainder of the circulating system or containing air under pressure above the surface of oil, is connected to the pipes 46 and 47 by a pipe 66. A manually-actuated valve 67 forms a means for opening and closing the pipe 66 at will. A pipe 68 connects the discharge orifice of 60 the pump 60 with the reservoir 65. The pipe 68 may be opened or closed at will by

operating manually-actuated valves 69. A check valve 70 is also provided in the pipe 68 to prevent oil from flowing from the oil reservoir 65 back through the pump 60. An oil supply receptacle 71 is connected to the pipe 54 through a valve 72. A pipe 73 which may be opened or closed at will by a manually-actuated valve 74, leads from the supply receptacle 71. The pipe 73 leads to any suitable sump. The drain pipes 42 of the transformer are connected to a pipe 75 which, in turn, is connected to the pipe 73 leading to the sump or other receiver for the discharge oil. A valve 76 closes the pipe 73 below the point of connection with it of the pipe 75. When it is desired to draw oil from one or both of the transformers, the oil withdrawn may be either discharged through the lower portion of the pipe 73 or into the receptacle 71 which for this reason should be below the transformers.

The oil-cooling device 49 may be of any suitable type. Each may advantageously consist of a coil of pipe 77 (shown in dotted lines in the left-hand device 49, only in Fig. 9), the ends of which are connected to the appropriate pipes 48 and 63. Each coil 77 is surrounded by a cylinder 78. An inlet pipe 79 leads to each cylinder 78 from a suitable source of water, such as a well. An outlet pipe 80 leads from each cylinder and is connected to a suction pump 81. The pipes 80 are connected together and valves 82 are employed whereby on occasion a circulation of water may be obtained through one or both cylinders 78 by means of one or both of the pumps 81. It will be observed that pumps 81 are arranged to draw rather than to force the water through the cylinders 78. This arrangement I prefer because I wish at all times to maintain the pressure of the water in the cylinders below that of the pressure of the oil in the coils of pipe 77 so that in case of any leakage in the coils of pipe 77, oil will flow into the water rather than water into the oil.

As a precaution against a possible failure of the pumps 81, I may provide means for obtaining a flow of water through the cylinders in the following manner: Water under considerable pressure is supplied to the pipes 83 from a supply pipe 84 which may lead from any suitable source, such as the mains of a municipal water supply system, or the like. In case the original source of energy of the system, of which the transformer forms a part, is a water power, the supply pipe 84 may lead from the main water reservoir. The pipes 83 are connected to suitable injector pumps 85 by means of which water is drawn into the cylinders through the pipes 79. Suitable valves 86 and 87 are employed to close the pipes 83 and the discharge pipes 88 from the injector pumps 85 respectively. By the use of these

injector pumps the water under pressure is more efficiently employed than would be the case if it were passed directly through the cooling coils of the devices 49.

In the normal operation of the device the pumps 81 draw water through both cooling devices 49, and the pump 59 draws oil out of each transformer through the pipes 51 and 53 and forces it into the cooling device 10 through the pipe 62 and pipes 63. From the cooling device the oil is forced through pipes 48, 47 and 46 into the oil supply pipes 32 of the transformer. When the transformer tanks are to be filled with oil or an additional supply of oil is to be forced into the transformer, the oil may be drawn directly from the oil supply tank or it may be drawn from the reservoir 65. The reservoir 65 is filled from the supply tank 71 through the pump 60. Ordinarily the reservoir 65 is kept full or nearly so and serves as a stand pipe regulating the head against which the pump 59 works. Should the cooling devices 49 become inoperative for any reason, as from a failure of water, the transformers may be cooled for a while at least by the oil supplied to them from the reservoir 65. Similarly, should the pump 59 become inoperative, the oil circulation may be 30 continued by the flow from the reservoir 65. Should the oil relied upon for cooling the transformer contain moisture, as it may at one time or another, the oil may be dried or dehydrated in the circulating system. To accomplish this I connect to one or both of the water supply pipes 79 a steam supply pipe 89 having a valve 90, and provide a pipe 91 and valve 92 controlling it for admitting air into the oil in the pipe 57. I arrange so that the steam admitted to pipe 79, when the valve 90 is open, shall be at about atmospheric pressure. This steam of course in circulating through the pipes of the cooling device serves to heat the oil and air entering through the pipe 91. As a result, the air rises to the top of the oil in the transformer receptacles carrying with it the moisture. Provision may be made for the removal of the moisture-laden air in any suitable manner. For instance, a pipe 93 normally closed by a valve 94 may lead from the top of each transformer casing. This pipe may advantageously be connected to a vacuum pump 95. By this means the oil 55 when containing moisture may be dried in a few minutes, after which the valves 90 and 92 are closed and the transformer and cooling system are then in condition to operate in the usual manner. Should the moisture in the oil be insufficient in amount to prevent the safe operation of the transformer under load conditions, the oil may be dried by mixing it with air admitted through the port into the pipe since the heat 60 imparted to the oil by the transformer core

and windings may be relied upon to cause the air to take up the moisture and be driven out of the oil.

While in the form of my invention hereinbefore described I have shown the laminae 70 extending horizontally, my invention is readily applicable to a transformer in which the laminae are vertical as shown in Fig. 7, in which the core bundles 9', windings inclosing casing 25', boxes 20', supply pipes 34' and 75 pipe 35' correspond to the parts 9, 23, 26, 34 and 35 respectively in the construction heretofore described. This construction possesses certain advantages over that in which the laminae are horizontal, especially for 80 transformers of very large size. When the transformers are horizontal as in the construction first described, it is necessary to provide substantial supports for the portions of the core surrounded by the windings for each phase, as otherwise the core tends to sag at that point. This of course 85 lengthens the windings and thereby increases the weight of the copper used and the cost of the transformer. When the laminae are arranged vertically each laminae 90 supports itself.

Another advantage possessed by the perpendicular laminae comes from the fact that the windings are then supported by engagement of their two long sides with the core where, with the laminae horizontally disposed, practically the entire weight of the winding must be supported by the top portion of the winding. It will be readily evident that the cooling system hereinbefore 100 described makes the vertical construction readily feasible since by it a transformer can be properly cooled in a manner not readily attainable if no such forced circulation were employed. 105

While the forms of my invention hereinbefore described and illustrated have been found to give excellent results in practice, it will be understood by those skilled in the 110 art that changes may be made in the form of my invention without departing from its spirit, and I do not wish the claims herein-after made to be limited to the specific embodiment disclosed more than is made necessary by the state of the art. 115

What I claim as new and desire to secure by Letters Patent of the United States, is,—

1. In combination, a casing filled with oil or other insulating fluid, a transformer immersed therein comprising core and coil portions, the transformer being provided with independent ventilating spaces for the core and coils discharging into the casing, a 120 closed chamber at one end of said transformer communicating with said independent ventilating spaces, and a circulating system arranged to deliver insulating fluid to the said closed chamber and to withdraw 125

130

- the same from the top of the transformer casing.
2. In combination, a casing filled with oil or other insulating fluid, a transformer immersed therein comprising core and coil portions the transformer being provided with independent ventilating spaces for the core and coils discharging into the casing, and a circulating system arranged to direct a flow of insulating fluid through said independent ventilating spaces into the casing and to withdraw the same from the top of the casing.
3. In combination, a casing filled with oil or other insulating fluid, a transformer immersed therein comprising core and coil portions the transformer being provided with independent ventilating spaces for the core and coils discharging into the casing, and a circulating system connected to each of the said independent ventilating spaces and to the transformer casing near the top thereof so as to direct independent streams of insulating fluid respectively through ventilating spaces for the core and the winding.
4. In combination, a casing filled with oil or other insulating fluid, a transformer immersed therein comprising core and coil portions the transformer being provided with independent ventilating spaces for the core and coils discharging into the casing, a circulating system connected to each of the said independent ventilating spaces and to the transformer casing near the top thereof so as to direct independent streams of insulating fluid respectively through the ventilating spaces for the core and the winding, and means for controlling the flow of the liquid in said circulating system.
5. In combination, a casing filled with oil or other insulating fluid, a transformer immersed therein comprising a core portion made up of laminae assembled in sections separated from each other to provide ventilating openings between adjacent sections, and coil portions having ventilating openings therethrough, a tubular casing separating the winding from the core and spaced therefrom so as to render the core ventilating passages independent of the passages through the coils, and a circulating system comprising means for directing a flow of insulating fluid through said independent ventilating spaces.
6. In combination, a casing filled with oil or other insulating fluid, a transformer immersed therein comprising a core portion made up of laminae assembled in sections separated from each other to provide ventilating spaces between adjacent sections, a coil portion having ventilating spaces therethrough, a tubular casing separating the winding from the core and spaced therefrom so as to form ventilating passages for the core independent of the passages through the coils, a closed casing extending from one end of the core portion of the transformer and inclosing the aforesaid tubular casing and the end of the transformer winding, and means for feeding the insulating fluid to said closed casing and withdrawing it from the top of the casing in which the transformer is immersed.
7. In combination, a casing filled with oil or other insulating fluid, a transformer immersed therein comprising a core portion made up of laminae assembled in sections with ventilating spaces between adjacent sections, means forming said spaces and adapted to increase the same in thickness from the bottom to the top of the core, a coil portion having ventilating spaces therethrough, a tubular casing separating the winding from the core and spaced therefrom so as to form ventilating passages for the core independent of the passages through the coils, a closed casing extending from the bottom of the core portion of the transformer and inclosing the aforesaid tubular casing and the lower end of the transformer winding, and means for feeding the insulating fluid to said closed casing and withdrawing it from the top of the casing in which the transformer is immersed.
8. In combination, a casing filled with oil or other insulating fluid, a transformer immersed therein comprising core and coil portions the transformer being provided with independent ventilating spaces for the core and coils discharging into the casing, a circulating system arranged to direct a flow of insulating fluid through said independent ventilating spaces and having a discharge pipe leading from the top of the casing, and means for maintaining the oil level in the transformer above the upper end of the discharge pipe when the system is in operation.
9. In combination, a casing filled with oil or other insulating fluid, a transformer immersed therein comprising core and coil portions the transformer being provided with independent ventilating spaces for the core and coils discharging into the casing, and a circulating system comprising means for directing the flow of insulating fluid through said independent ventilating spaces.
10. In a cooling system for electrical apparatus, means for obtaining a forced circulation of a fluid insulator through one portion of a cooling device and for obtaining a forced circulation of a cooling agent for the insulator through another portion of the device, and means by which when desired air may be mixed with the insulator and the cooling agent may be replaced by a heating agent.
11. In combination, a receptacle, a transformer located therein, means for forcing a cooling fluid insulator through said receptacle.

ceptacle comprising an inlet pipe and an outlet, said outlet being located beneath the normal level of the fluid insulator in said receptacle, and means for mixing air when desired with the insulating fluid entering said receptacle.

12. In combination, a normally closed receptacle, a transformer located therein, means for forcing a cooling fluid insulator through said receptacle, said means including an inlet and an outlet, said outlet being located beneath the normal level of the fluid insulator in said receptacle, means for mixing air when desired with the insulating fluid entering said receptacle, and means for removing air from said receptacle.

13. In a multiphase shell-type transformer, a core portion and winding surrounding it for each phase, a casing surrounding each winding and separating it from the core, said casing having its ends open, a receptacle for each phase secured to one side of the core with one end of the corresponding casing projecting into it, means for introducing a cooling fluid into each receptacle and for causing it to pass out therefrom partly through said casing to cool the winding and partly without said casing to cool the core.

14. In a shell-type transformer, a core portion, ventilating passages therefor, a winding surrounding said core portion, a casing separating said winding from the core, a receptacle secured to one side of said core with its side adjacent the core open, one end of said casing projecting into said receptacle, and means for causing a cooling fluid to pass from said receptacle through said casing and through the passages.

15. In combination, a core portion formed of bodies of laminae of magnetic material, adjacent bodies being separated by spaces, means forming said spaces adapted to increase the same in thickness from the bottom to the top of the core, a bath of oil in which said core is immersed, and means for maintaining a difference in the pressure of said oil at opposite sides of said body whereby oil is caused to flow through said spaces.

16. In combination, a core formed of laminated bodies of magnetic material, adjacent bodies being separated by spaces, means forming said spaces adapted to increase the same in thickness from one end of the core to the opposite end of the core, said core being pierced by a conductor-receiving opening or passage extending transversely to the laminae, and means for causing oil under pressure to enter the end of said passage at one end of the core.

17. In combination, a core portion formed of bodies of parallel laminae of magnetic material, adjacent bodies being separated by spaces parallel with the laminae extending from one side of said portion to the other, means forming said spaces adapted to in-

crease the same in thickness from one end of the core to the other, a bath of oil in which said core portion is immersed, and means for maintaining a difference in the pressure of said oil at opposite sides of said portion and at opposite ends thereof whereby oil is caused to flow through the said spaces in a predetermined manner.

18. In combination, a receptacle, an electrical device therein, means for obtaining a circulation of a cooling fluid through said receptacle including an outlet passage and a valve controlling the same, and means for automatically maintaining said valve closed except when the level of the cooling liquid in said receptacle is some distance above said outlet passage.

19. In combination, a receptacle, a bath of oil in said receptacle, an electrical device immersed therein, a conduit supplying cold oil under pressure to said engagement, a discharge orifice through which hot oil is sucked out of the receptacle, and a float operated valve controlling it arranged to automatically maintain the level of the oil in the receptacle above the discharge orifice.

20. In a transformer, a core, a winding surrounding a portion thereof, a casing separating the winding from the core, a box-like receptacle secured against the core with said casing projecting into it, a tank in which said core, winding and receptacle are contained, means for admitting a fluid insulator under pressure into said receptacle, and means including an outlet located above said core, winding and receptacle for withdrawing said insulator from said tank.

21. In combination, a receptacle, a transformer contained therein, means for obtaining a circulation of a fluid insulator through said receptacle, and means for cooling said fluid insulator comprising two chambers adjacent each other, and means for forcing water through one of said chambers and for forcing the fluid insulator through the other of said chambers so arranged that the pressure in the chamber containing the fluid insulator is greater than in the other chamber.

22. In combination, a casing filled with oil or other insulating fluid, a transformer immersed therein comprising core and coil portions the transformer being provided with independent ventilating spaces for the core and coils discharging into the casing, a circulating system arranged to direct a flow of insulating fluid through said independent ventilating spaces into the casing and to withdraw the same from the top of the casing, and means for cooling the liquid.

23. In combination, a casing filled with oil or other insulating fluid, a transformer immersed therein comprising core and coil portions the transformer being provided with independent ventilating spaces for the core and coils discharging into the casing,

a circulating system arranged to direct a flow of insulating fluid through said independent ventilating spaces into the casing and to withdraw the same from the top of the casing, and means for dehydrating the liquid.

24. In combination, a casing filled with oil or other insulating fluid, a transformer immersed therein comprising core and coil portions the transformer being provided with independent ventilating spaces for the core and coils discharging into the casing, a circulating system arranged to direct a flow of insulating fluid through said independent ventilating spaces into the casing and to withdraw the same from the top of the casing, means for cooling the liquid, and means for dehydrating the same.

25. The combination with a transformer having a casing, a winding comprising a plurality of spaced coils, a laminated core structure, the transformer being provided with ventilating spaces for said coils and said core structure, and an insulating liquid, of means for directing independent streams of the liquid respectively into the spaces for the core and for the winding, means for regulating the volume of the streams and means for withdrawing the united volumes of liquid from the top of the casing.

In witness whereof, I have hereunto set my hand this 2nd day of April, 1906.

WALTER S. MOODY.

Witnesses:

BENJAMIN B. HULL,
HELEN ORFORD.

Correspondence
Letters Patent No. 1,141,199.

It is hereby certified that in Letters Patent No. 1,141,199, granted June 1, 1915, upon the application of Walter S. Moody, of Schenectady, New York, for an improvement in "Three-Phase Transformers," an error appears in the printed specification requiring correction as follows: Page 7, line 86, for the word "engagement" read *receptacle*; and that the said Letters Patent should be read with this correction therein that the same may conform to the record of the case in the Patent Office.

Signed and sealed this 3rd day of August, A. D., 1915.

[SEAL.]

R. F. WHITEHEAD,
Acting Commissioner of Patents.
